D. L. CHESTERMAN.
PAD FOR A HERNIAL TRUSS.
APPLICATION FILED APR. 1, 1915.

1,176,431.

Patented Mar. 21, 1916.

UNITED STATES PATENT OFFICE.

DANA L. CHESTERMAN, OF PHILADELPHIA, PENNSYLVANIA, ASSIGNOR TO CHESTERMAN AND STREETER, OF PHILADELPHIA, PENNSYLVANIA, A CORPORATION OF PENNSYLVANIA.

PAD FOR A HERNIAL TRUSS.

1,176,431.

Specification of Letters Patent. Patented Mar. 21, 1916.

Application filed April 1, 1915. Serial No. 18,497.

To all whom it may concern:

Be it known that I, DANA L. CHESTERMAN, a citizen of the United States, residing in the city and county of Philadelphia, 5 State of Pennsylvania, have invented a new and useful Pad for a Hernial Truss, of which the following is a specification.

My invention relates to a hernial truss and consists of a pad therefor formed with 10 a protuberant portion and a base rim or lower tier in a plane different from the top of said portion, whereby the pad will hold a rupture with greater certainty owing to said protuberant portion being adapted to 15 cover the orifice just above the pubic bone, while the underneath rim or tier rests across said pubic bone, whereby said protuberant portion prevents the escape of the rupture through said orifice or the blocking of the 20 latter.

The invention is satisfactorily illustrated in the accompanying drawing, but the important instrumentalities thereof may be varied, as long as they are included in the 25 scope of the claim.

Figure 1 represents a perspective view of a pad of a hernial truss embodying my invention, including also the members of the truss to which said pad is applied. Fig. 30 2 represents a front elevation of the pad and adjacent portion. Fig. 3 represents a longitudinal section thereof on the line $x-x$ Fig. 2. Fig. 4 represents a transverse section thereof of a portion on the line $y-y$ Fig. 3. Fig. 5 represents an elevation of 35 a portion of the pad. Fig. 6 represents an elevation of the interior of the pad, partly broken away.

Similar numerals of reference indicate 40 corresponding parts in the figures.

Referring to the drawings:—1 designates a pad of a truss, 2 the body belt or band on which the same is mounted, and 3 the perineal strap which is attached to said pad 45 and extends to the rear of said belt with which it is adjustably connected by a buckle or other suitable means.

The pad 1 consists of a mat forming a 50 comparatively flat back member and a protuberance or protruding member 5 which latter is superimposed on said mat and projects outwardly therefrom, said mat being composed of a piece 4 of felt or other suitable pliable material and said protuberance 55 being formed of a mass of soft material as

cotton, said mass being incased in the covering member or incasement 6 of leather or the like, said member 6 and the mass being connected by stitches 7 which are passed through said cover member around 60 what may be termed the base of the mass, so as to confine the mass in said covering member and preserve the form of the protuberance 5, and prevent the latter from spreading at its base leaving the tier or 65 rim portion 8 of the pad circumscribing said base and extending comparatively flat laterally from said base protuberance, thus making the pad of two different levels viz., at the crown of the protuberance and the 70 outer face of said portion 8. When the truss is in use, while the protuberance 5 forms a depression in the outer face of the abdomen, the flesh around the depression will be bridged from the latter to the rim 75 8, and contact with said rim, and so passed freely over the stitches 7 without liability of the flesh contacting therewith since said stitches are sunken in the outer face of the pad between the protuberance and rim 80 at the base of the former and the inner circumference of the latter.

On the back of the mat is the plate 9 of metal or other rigid material, the same being incased in a pad 10 of fabric, this being covered by the backing 11 of leather or other suitable material to which is stitched said incasement 6 which is turned in over the side portions of the mat 4, thus closing the back of the pad 1, as best 85 shown in Figs. 2 and 4. Riveted or otherwise connected with said plate 9, as at 12 is one end of the adjacent soft portion 13 of the perineal strap 3, which portion passes from said plate through the neck 13 of the 90 pad outside of the same and joins said portion of said strap 3 which is to be adjusted and secured by the buckle 14.

Placed upon the backing 11 is the metal plate 15 for attachment of the pad with 100 the members of the body belt 2, said plate being secured in position by the screws 16 which pass through the pad and engage with the plate 9 which is provided with threaded openings 17 for that purpose. 105

Of course, the protuberance may be formed of a bag inflated with air or fluid in lieu of the cotton material filling the shaped-covering member 6, it being seen that in all cases the lower rim or tier is 110

adapted to rest on the pubic bone and the protuberance is adapted to hold the rupture with great certainty without liability to sink into the abdomen and block the orifice within the same.

Having thus described my invention what I claim as new and desire to secure by Letters Patent, is:—

A pad for a hernial truss composed of a 10 back member formed of pliable material and a protuberance formed of pliable material projecting outwardly from a portion of said back member, leaving the latter

with an exposed rim in front, the base of said protuberance joining the inner wall of 15 said rim, a covering for said protuberance and back member, and means securing said protuberance to said back member and consisting of stitches passed through said covering around the base of said protuberance 20 and into said back member at the inner wall of the rim thereof.

DANA L. CHESTERMAN.
